THERMALLY ACTUATED AUTOMATIC
OVERLOAD CIRCUIT BREAKER

Ross E. Locher, San Marino, Calif., assignor to
Zinco Electrical Products, Los Angeles, Calif.,
a corporation of California

Application October 29, 1951, Serial No. 253,655

3 Claims. (Cl. 200—116)

1

My invention relates to automatic circuit breakers which are hereby defined as devices through which an electric current is passed and which open the circuit and automatically interrupt said current whenever certain undesired conditions occur in the circuit.

My invention relates to a device by which the circuit is interrupted whenever the current in the circuit so increases that it is desirable to open the circuit.

My invention further relates to such an over-load circuit breaker which opens whenever a thermostatic member forming a part of the breaker is heated above a predetermined temperature.

During the last twenty years there has been a strong tendency to replace fuses by thermally operated, automatic, over-load circuit breakers, especially for use on circuits supplying current for domestic use, a field at one time wholly occupied by fuses. In spite of strong efforts to make the replacement of fuses easy and safe, these efforts were not entirely successful and there has been an increasing demand for circuit breakers for use in domestic service. Such breakers are used only on 110 or 220 volt service and have a rated full load capacity of 50 amp. or below. They are used on both A. C. and D. C. circuits. It is an object of my invention to provide a novel and useful circuit breaker adapted to meet the demand for such domestic breakers.

For some time there have been many circuit breakers available for use in such service but such breakers have cost the consumer several dollars, whereas the fuses and fuse blocks usually supplied for this service cost only a small fraction of a dollar. It is a further object of my invention to provide a circuit breaker which will adequately perform the functions needed in domestic service and which, when made under good manufacturing, costs little more than the fuse block and fuse.

These breakers are usually installed in metal boxes with a hinged cover and such boxes often also carry the watt-hour meter. An ordinary house will have several circuits each protected by a circuit breaker, all of these breakers being placed for convenience in a single box at a central location. To be salable, the box must be small. It is a further object of my invention to provide a circuit breaker which will occupy very little space so that a plurality of them can be mounted in a single box.

It is desirable to supply such breakers in various capacities, for example, 15, 25, 30, 40 and 50 amp., that is to say, to supply circuit breakers

2

which can be set to open on an overload of 15, 25, 30, 40 or 50 amp. At the present time the breakers are built and adjusted at the factory to open at a single definite amperage so that a supply house has to carry at least five sizes of such breakers. It is a further object of my invention to provide a breaker which can be adjusted to open at any one of several over-load values.

Further objects and advantages of my invention will be made evident hereinafter.

The invention resides in new combinations of elements by which the above recited objects are attained. The particular embodiment of the invention illustrated in the drawing, and herein-after described, consists of a box and a movable assembly mounted in the box, this assembly consisting of a sleeve movable axially in, and projecting outside of, one wall of the box, and a stem moving axially in, and having an outer end that, in certain positions of the parts, projects outside of, the outer end of the sleeve. To close the breaker, the sleeve and stem are pushed inwardly and to open the breaker the sleeve and stem are pulled outwardly. When the breaker opens on overload, the stem moves outwardly without moving the sleeve. The mechanism inside the box is very simple, the levers, toggles, and latches usually found in conventional circuit breakers being absent.

In the drawings which illustrate preferred embodiments of my invention:

Fig. 1 is a section on a plane indicated by the line 1—1 in Fig. 3 of the breaker in its closed position, the position of its stem and connected parts in the half-open position of the breaker being shown in dotted lines;

Fig. 2 is a section on the same plane as Fig. 1 of the breaker in its full open position;

Fig. 3 is a section on a plane indicated by the line 3—3 of Fig. 1;

Fig. 4 is a top view of the circuit breaker shown in Figs. 1, 2, and 3;

Fig. 5 is a view similar to Fig. 1 of a modified form of circuit breaker;

Fig. 6 is a section on an enlarged scale on a plane indicated by the line 6—6 of Fig. 2 of the device used to prevent rotation of the sleeve; and

Fig. 7 is a diagram showing how the current trip value of the breaker may be changed.

In the embodiment of the invention shown in the drawings the box or casing 11 is formed of molded material having good dielectric characteristics. A cover 12 secured by screws 13 encloses a central chamber 14 in the box 11. A first terminal member 15 and a second terminal

16 are embedded in and project from the bottom 17 of the box, as seen in Figs. 1, 2, and 5. Screws 18 are provided on the outer ends of each of the terminals 15 and 16. Wires from an external circuit may be connected to the terminals 15 and 16 by use of the screws 18 and the function of the circuit breaker is to maintain the continuity of said circuit as long as the circuit breaker is closed, and to open the circuit whenever the circuit breaker is manually or automatically opened because of an overload in the circuit.

Passing through, but rigidly secured in, the top 21 of the box 11 is a dielectric tube 22 which has a cylindrical bore in which a sleeve 23, preferably formed of material having good dielectric characteristics, can slide axially. Carried on and rigidly secured to the sleeve 23 is a brass shell 24 having two shallow grooves 25 and 26 formed therein, the outer surface of said shell 24 between and adjacent to the grooves 25 and 26 being toothed or indented as shown at 26' in Fig. 6. The upper end of the sleeve 23 is grooved as shown at 27 to form a knob 28. An important feature of the sleeve assembly is a calibration plate 29, preferably formed on the bottom of the brass shell 24, the periphery of the plate being eccentric to the axis of the sleeve 23.

Mounted in a cavity 31 in the top 21 is a ball 32 which is forced toward the axis of the sleeve 23 by a spring 33 held in place by a screw 34. The ball projects through the dielectric tube 22 and engages the upper groove 25 whenever the breaker is closed, engaging the lower groove 26 whenever the circuit breaker is opened manually. The ball 32 and grooves 25 and 26 form a convenient friction producing device adapted to tend to hold the sleeve 23 in either extreme position, and to allow the operator to move the sleeve 23 from either extreme position to the other position by pulling or pushing on the knob 28.

Sliding freely in a hole extending through the sleeve 23 is a stem 41 which has a knob 42 at its upper end, the knob 42 being entirely inside a cavity formed in the top of the sleeve 23 when the stem 41 is in its lowest position with relation to the sleeve 23. The lower end of the stem 41 passes through a lug 43 projecting from, and preferably formed as a unitary part of, the box 11. The stem 41 is acted upon by a spring which tends to force the stem 41 upwardly in the sleeve 23. Two methods of so mounting the spring are shown in Figs. 1 and 5 and other methods might, of course, be used. Fig. 5 shows a compression spring 44 in the cavity which contains the knob 42, and Fig. 1 shows a compression spring 45 pressing against the lug 43 and against a pin 46 carried by the stem 41.

Rigidly secured to the stem 41 near the lower portion thereof is a bimetallic, thermally responsive strip 51 which is bent out to miss the lug 43 and up so that its upper end may engage the calibration plate 29. The upper end of the strip 51 is connected to the terminal 16 through a flexible lead 52, current passing through said lead 52, the strip 51, and the stem 41 to a stationary contact 53 formed on the terminal 15 whenever the circuit breaker is closed. The bend in the strip 51 is engaged in a slot 54 formed in a projection 55 from the box 11 so that the strip 51 and the stem 41 to which it is rigidly attached cannot turn with relation to the box 11. The sleeve 23 can, however, turn in the box 11 but is frictionally restrained from turning by a spring detent 56 (Fig. 6) placed in a cavity 57 in the top 21 of the box 11. The free end of

the detent 56 engages the knurling 26' on the shell 24 but may be readily released if the sleeve 23 is turned by turning the knob 28.

The strip 51 is formed of two metals having radically different rates of heat expansion, such thermally responsive bimetallic members being commonly used for many purposes. When heated, a flat portion of such a strip tends to assume an arcuate shape and if one end of such a strip is held rigid, the other end of the strip tends to move in a direction perpendicular to the plane of the strip. When the member 51 is heated by the passage of electric current therethrough, the upper end of the strip tends to move away from the stem 41. The amount of heating of the strip and the consequent movement of the upper end of said strip are functions of the C^2R loss in the strip.

The strip 51 performs a double function as it is not only a heat responsive member but it also acts as a latch. When the strip 51 is cold, its upper end engages the calibration plate 29, being held in contact with that plate by either the spring 44 or the spring 45 so that the stem with its knob 42 inside the cavity of the sleeve 23 moves in and out with the sleeve 23. When the sleeve is pushed toward the box 11, the stem 41 moves down and engages the stationary contact 53 and the circuit is closed. If the knob 28 is pulled away from the box 11, the stem 41 moves with the sleeve 23 and the circuit is opened.

If, however, the calibration plate 29 is engaged by the upper end of the strip 51 in the position shown in Figs. 1 and 5, and the strip is so heated that the upper end of the strip moves to the right and disengages from the calibration plate 29, the spring 44 or 45 will jerk the stem 41 up and thus open the circuit. In other words, the circuit will be opened whenever the current in the circuit exceeds a pre-established or calibrated value.

It is for the purpose of making it possible to set the circuit breaker to open at any one of several current values that the calibration plate is made eccentric to the fixed axis of the sleeve 23, which is also the fixed axis of the stem 41. As the sleeve 23 is rotated about this axis and the eccentric calibration plate 29 is turned, the distance through which the end of the strip 51 must move may be varied. Referring to Fig. 7, the sleeve 23 may be turned through 180° so that the calibration plate assumes either the position A or the position B. In position A the end of the strip 51 needs to move only the distance a to release, while in position B the end of the strip 51 must move the distance b . Obviously, only a higher current value will move it this longer distance.

The method of operation of the invention is as follows: If the circuit breaker has been opened manually, the parts will be in the position shown in Fig. 2 in which the sleeve 23 has been pulled to its open or outer position, the ball 32 resting in the lower groove 26 and the upper end of the strip 51 being below and latched against the calibration plate 29. The breaker can be closed by pushing in on the end of the sleeve 23, the ball 32 then engaging the upper groove 25 and holding the sleeve 23 in its lower position (Figs. 1 and 5). The stem 41 moves with the sleeve 23 during said manual closing, being held in fixed relationship with the sleeve by the strip 51, acting as a latch, and the spring 44 or 45.

If, while the parts are in the closed position as in Fig. 5 or as shown in full lines in Fig. 1, an overload occurs, that is, current in excess of a

predetermined amperage flows in the circuit protected by the breaker, this current must pass from the terminal 15 to the terminal 16 or vice versa. In this passage, the current must pass through the bimetallic strip 51. It is a characteristic virtue of this strip that it responds only very slightly to momentary overloads which do not heat the strip to such a degree that it unlatches from the calibration plate 29. The apparatus protected by the circuit breaker is not vulnerable to such momentary overloads. If, however, the overload persists for a sufficient time, the upper end of the strip 51 moves to the right as shown in the drawing and the spring 44 or 45 snaps the stem up into half open position as shown in dotted lines in Fig. 1. In this position the sleeve 23 remains in its lower position as shown in Figs. 1 and 5 but the stem is in its upper position, the knob 42 projecting from the upper end of the sleeve 23. The length of the sleeve is such that when it is pushed down it will reset the strip 51 as a latch, the upper end of which catches the calibration plate 29.

To reset the breaker, it is necessary to pull the sleeve 23 into its upper position, as shown in Fig. 2. As it is pulled up, the strip 51 strikes against the lug 43 and is held so that the upper end of the strip 51 can latch under the calibration plate 29. The breaker is then in the open position shown in Fig. 2 and it can be closed by pushing the sleeve 23 from its upper position to its lower or closed position as shown in Fig. 5 and in full lines in Fig. 1. It is an advantage of this breaker that if the sleeve 23 is pushed into its closed position, as shown in Fig. 5, before the conditions producing the overload are remedied, the breaker will open even if the sleeve 23 is held in its closed position.

The calibration of the circuit breaker is adjusted at the factory to open on any overload within a certain range; for example, between 10 and 50 amperes. Referring to Fig. 7 in which the calibration plate 29 is shown in full lines A with the breaker set to trip at a sustained overload of 10 amperes, as shown by the arrow 61, on the top of the sleeve 23, which points to a calibration mark 10 on the outside of the top of the box 11. The end of the strip 51 is shown in full lines in its cold position and it will be evident that when it is heated enough to move through the distance a to the position 62, it moves away from the plate 29 and the circuit breaker will open. However, if the sleeve 23 is turned through an angle of 180° so that the arrow 61 points to the calibration mark 50, the calibration plate 29 is turned into the dotted line position B and the end of the strip 51 must move to a position 63 through a distance b to allow the breaker to open. This will only occur when the strip has had a sustained overload of 50 amperes. Obviously, the plate 29 need not be of circular contour but may have a cam-shaped configuration between the calibration marks 10 and 50.

I claim as my invention:

1. A circuit breaker comprising: a hollow casing of insulation material having an axial bore in one wall thereof; a cylindrical sleeve of insulation material having a calibration plate secured to the lower end thereof, said sleeve being mounted to move axially in said hollow casing with its outer end at all times in a position to be available to an operator; friction means for restraining the movement of said sleeve in its open or extreme outer axial position and in its closed or extreme inner position; a stem having its inner

portion of conductive material and extending through said sleeve and adapted to move axially with relation thereto from an open or extreme outer axial position to a closed or extreme inner position; a stationary contact fixed with relation to said hollow casing in such position as to be in electrical contact with the inner end of said stem when both the stem and sleeve are in their inner or closed positions, said stationary contact being provided with means for connecting it in the circuit to be interrupted by said circuit breaker; a thermostatic element rigidly secured to said inner conductive portion of said stem near the lower end of said stem, the upper end of said element being in such a position that, when cold, it engages said calibration plate on the lower end of said sleeve and thus holds said stem in its closed or lower position with relation to said sleeve; and a flexible conductive member connected at one end in the circuit to be interrupted by the circuit breaker and at the other end to said thermostatic element in such a position as to cause current to flow through said thermostatic element whenever the circuit breaker is closed and current flows in said circuit.

2. A circuit breaker comprising: a hollow casing of insulation material having an axial bore in one wall thereof; a cylindrical sleeve of insulation material having a calibration plate secured to the lower end thereof, said sleeve being mounted to move axially in said hollow casing with its outer end at all times in a position to be available to an operator; friction means for restraining the movement of said sleeve in its open or extreme outer axial position and in its closed or extreme inner position; a stem having its inner portion of conductive material and extending through said sleeve and adapted to move axially with relation thereto from an open or extreme outer axial position to a closed or extreme inner position; a stationary contact fixed with relation to said hollow casing in such position as to be in electrical contact with the inner end of said stem when both the stem and sleeve are in their inner or closed positions, said stationary contact being provided with means for connecting it in the circuit to be interrupted by said circuit breaker; a lug projecting from said hollow casing, the lower portion of said stem passing through an opening through said lug; a compression spring surrounding said stem above the lug, one end of said spring pressing on said lug and the other end of said spring pressing on a projection on said stem, said spring being of such length that it is under compression whenever said stem is in its inner or closed position, said spring being too weak to force said sleeve out of its inner or closed position; a thermostatic element rigidly secured to said stem near the lower end of said stem, the upper end of said element being in such a position that, when cold, it engages said calibration plate on the lower end of said sleeve and thus holds said stem in its closed or lower position with relation to said sleeve; and a flexible conductive member connected at one end in the circuit to be interrupted by the circuit breaker and at the other end to said thermostatic element in such a position as to cause current to flow through said thermostatic element whenever the circuit breaker is closed and current flows in said circuit.

3. A circuit breaker comprising: a hollow casing of insulation material having an axial bore in one wall thereof; a cylindrical sleeve of insulation material having a calibration plate secured to the lower end thereof, said sleeve being

mounted to move axially in the bore of said hollow casing with its outer end at all times in a position to be available to an operator; friction means for restraining the movement of said sleeve in its open or extreme outer axial position and in its closed or extreme inner position; a stem having its inner portion of conductive material and extending through said sleeve and adapted to move axially with relation thereto from an open or extreme outer axial position to a closed or extreme inner position; a stationary contact fixed with relation to said hollow casing in such position as to be in electrical contact with the inner end of said stem when both the stem and sleeve are in their inner or closed positions, said stationary contact being provided with means for connecting it in the circuit to be interrupted by said circuit breaker; a compression spring placed in a cavity in the outer end of said sleeve and surrounding the stem, the inner end of said spring bearing on 15 said sleeve and the outer end of said spring bearing on a projection from said stem, said spring being of such length as to be under substantial compression when said stem is in its lower or closed position; a thermostatic element rigidly 20 25

5
10

secured to the conductive portion of said stem near the lower end of said stem, the upper end of said element being in such a position that, when cold, it engages said calibration plate on the lower end of said sleeve and thus holds said stem in its closed or lower position with relation to said sleeve; and a flexible conductive member connected at one end in the circuit to be interrupted by the circuit breaker and at the other end to said thermostatic element in such a position as to cause current to flow through said thermostatic element whenever the circuit breaker is closed and current flows in said circuit.
